UNITED STATES PATENT OFFICE.

MICHAEL A. POPKESS, OF KANSAS CITY, MISSOURI, ASSIGNOR TO BITUMINIZED ROAD COMPANY, OF PHOENIX, ARIZONA, A CORPORATION OF ARIZONA.

PROCESS FOR MAKING ROADWAYS, RAILROAD-BEDS, SIDEWALKS, AND THE LIKE.

1,076,782.

Specification of Letters Patent.

Patented Oct. 28, 1913.

Application filed October 28, 1908. Serial No. 459,956.

To all whom it may concern:

Be it known that I, MICHAEL A. POPKESS, a citizen of the United States, residing at Kansas City, in the county of Jackson and State of Missouri, have invented certain new and useful Improvements in Processes for Making Roadways, Railroad-Beds, Side-walks, and the like, of which the following is a specification.

This invention consists in a process of surfacing roadways, and its object is to produce an economical, durable, waterproof surface, which shall be to a certain degree malleable, so that it will not crack nor disintegrate under traffic. This object is attained by obtaining an intimate admixture or combination of the earthy material, which constitutes the present surface of a majority of roads, with a liquefied asphaltic binder. This result has not hitherto been obtained, as far as I am aware, by the methods used, which consist in harrowing up the surface and then sprinkling it with a binder. The reasons why such methods have not proved satisfactory is because an imperfect admixture only is obtained. The earth, soil or loam, composing the surface of ordinary roadways, contains a large amount of moisture, in other words, is cold and damp, and, consequently, the bituminous binder, when the sprinkling method is followed, chills and congeals as soon as it comes into contact with the earthy material, the result of which is to cause it to mix unevenly with said material, so that the resultant surface is more or less un-uniform, some portions having sufficient or too much binder and other portions having none or too little. In order to obtain a uniform and complete impregnation of the binder, I have discovered that the earthy material must be substantially free from stone, gravel or sand, must be dry and must be prevented from chilling or congealing the binder before it has time to become thoroughly commingled or combined therewith. To accomplish these objects, I introduce the binder at a point considerably below the actual surface, in most cases preceding this operation by introducing heat in the same way, a means which I have devised for the purpose being shown in the accompanying drawing, in which:

Figure 1, is a central vertical longitudinal section of a part of a machine embody-

ing a plurality of teeth for embedment in the ground and capable for use as mediums for injecting heat or a binder in liquid condition into the ground from a point below the surface thereof. Figs. 2, 3 and 4, represent enlarged rear and side views and a central vertical section respectively, of one of the teeth or devices for injecting a heating medium into the ground at a point below the surface thereof. Figs. 5 and 6 are horizontal sections on the line A—A of Figs. 2, 3, and 4, Fig. 5 indicating a section in which the view is upward and Fig. 6 a section in which the view is downward. Figs. 7, 8, and 9 are views corresponding to Figs. 2, 3, and 4, respectively, of the construction of tooth for use in injecting a binder in liquid condition into the ground from a point below the surface thereof. Fig. 10, is a section on the line B—B of Figs. 7, 8 and 9.

1 indicates side bars and 2 end bars of a rectangular frame, only one each of the bars 1 and 2 appearing.

3 is a bottom and 4 a top for said frame, which bottom and top in conjunction with the bars, form a casing, and communicating with the chamber of said casing is a pipe 5 to supply thereto a suitable heating medium, such as gas for instance, or a binder in liquid condition.

The bottom is preferably extended forward and upward at its front end at 6 and at such end is equipped with eye-bars 7, to which one or more horses may be hitched and projecting from the sides of the frame are arms 8 (one only appearing) equipped with a roller 9 to roll on the surface of the ground and prevent the front teeth, hereinafter referred to, from digging too deeply therein or the end of the frame from swinging upwardly.

The teeth 10 depend rigidly from the bottom and preferably are substantially U-shape in cross section so as to provide chambers 11. At their upper ends the teeth are provided with enlargements or flanges 12 and with threaded stems 13 to extend up through the bottom, nuts 15 engaging the upper ends of said stems and the upper side of the bottom or the base flanges of cross bars 2 (see Fig. 1) to clamp the flanges or enlargements 12 firmly against the under side of the bottom. The teeth are also provided with threaded studs or bolts 14.

equipped with nuts 15' whereby plates 16, fitting in chambers 11 may be clamped firmly therein with a substantially fluid-tight relation, at a point about approximately centrally of the tooth so that the side walls of the latter may project a substantial distance beyond said plates and act as fenders to ward off or hold back the loose earth as the teeth are drawn through it, 10 for a purpose which hereinafter appears, the plates 16 being provided near their lower ends with orifices 17.

In Figs. 7, 8 and 9, the bolts or stems 13 are shown as and are preferably of greater length and mounted on said bolts and forming a closure for the rear side of the chamber 11 are plates 18 provided with notches 19 in their opposite edges, these notches forming jet-orifices for a liquid binder. 15 20 Assuming that the teeth 10 are of the type shown in Figs. 2 to 6 inclusive, they will be supplied with gas under pressure from the casing and the same will be ignited at jet orifices 17. The machine is then dragged over the ground like a harrow and the teeth will plow through said ground, the flame from the burner orifices impinging upon the ground to raise it to the desired temperature, the walls projecting rearwardly 25 30 beyond plates 16 guarding against extinction of the flame from the teeth by earth piling directly up against the back of said plates 16 and covering the orifices.

Assuming that the teeth employed are of the type shown in Figs. 7 to 10 inclusive, and receive binder in liquid condition under pressure from the casing, it will be apparent that such liquid binder will be in effect sprayed into the loose earth from the orifices 19 and thus become thoroughly intermixed with and incorporated in such earth as the teeth plow through the ground in the travel of the machine.

It will be seen that the bottom 3 of the 45 frame covers the material while it is being

mixed with the binder, thereby keeping it in place and preventing it from cooling too rapidly so as to congeal the binder before it has thoroughly impregnated the material. Naturally, when the material is already dry and not very cold, the preliminary step of heating it may be omitted.

Having thus described the invention what I claim as new and desire to secure by Letters-Patent, is—

1. The process of surfacing roadways and the like, which consists in simultaneously harrowing and heating below the surface the material of the roadway and then injecting a liquid binder into the heated material 60 below the surface thereof.

2. The process of surfacing roadways and the like, which consists in harrowing the material of the roadway, playing heat into the same from points below the surface 65 thereof and injecting a liquid binder into the same below the surface thereof.

3. The process of surfacing roadways and the like, which consists in plowing and smoothing the roadway material, simultaneously harrowing and playing heat into the same, injecting a liquid binder below the surface of the roadway and finally smoothing and compressing the same.

4. The process of forming a waterproof, 70 plastic surface for roadways and the like, which consists in injecting a hot, liquefied binder into the earthy material of the roadway to be paved at some distance below the surface thereof, while maintaining the surface covered and compressed, whereby the heat is retained until an intimate mixture of the earthy material and the binder has taken place.

In testimony whereof I affix my signature, 75 in the presence of two witnesses.

MICHAEL A. POPKESS.
